UNITED STATES PATENT OFFICE.

JAMES M. KENDALL AND JAMES PEEL, OF MADELIA, MINNESOTA.

IMPROVEMENT IN FANNING-MILLS.

Specification forming part of Letters Patent No. 129,965, dated July 30, 1872.

Specification describing a new and Improved Fanning-Mill, invented by JAMES M. KENDALL and JAMES PEEL, of Madelia, in the county of Watonwan and State of Minnesota.

Our invention consists of a simple and efficient arrangement of the shaking-shoe and a revolving screen, whereby the grain is first subjected to the blast in the shoe, and then passed through the screen, which is revolved by gearing connected with the fan-driving shaft, the said screen being protected from the blast of the fan by a hood. The invention also comprises a novel arrangement of the apparatus for shaking the shoe, whereby a horizontal and a vertical motion are imparted to the shoe. The invention also consists in constructing the shoe with perforated sides, as herein-after described.

Figure 1 is a side elevation of our improved fanning-mill. Fig. 2 is a longitudinal sectional elevation. Fig. 3 is a transverse sectional elevation taken on the line *xx* of Fig. 2. Fig. 4 shows the arrangement of the shaking apparatus.

Similar letters of reference indicate corresponding parts.

A represents the shoe, with the ordinary coarse riddles B, onto which the grain is delivered from the hopper C. The lower screen D of the shoe is made considerably shorter than in the mills as commonly arranged; and, besides slanting toward the fan, it also slants from the left to the right side of the machine, and is inclosed by the side pieces E and end piece F of screen-wire, except at the hole G, where a spout, H, is arranged to extend from the lowermost corner of said screen through the side of the case, and discharging into a spout, I, returning through the side of the machine into the screen K, arranged to extend through the case from side to side, and discharge at L. Said screen is made smaller at the end receiving the grain than at the other, in order to obtain sufficient descent for the lower side for causing the grain to work

through it and have the said receiving end as low as necessary to provide room for the screen-shoe above. This screen is fitted at the ends in the sides of the case for bearings to avoid the ordinary center shaft and journals. It is turned by a toothed rim, M, gearing with the wheel N on the crank-shaft O; but a belt and pulleys may be used instead of this gearing, if preferred. P represents a hood, introduced between the fan and the screen to protect the latter from the fan-blast. For shaking the shoe the cross-bar Q is connected to the bell-crank R, mounted in the side of the case by a rod, S, and this bell-crank is connected to the short crank U on the fan-shaft by the rod L. This gives the horizontal motion, and in order to give the vertical motion the rod S is arranged to slant downward from the bell-crank to the point of connection with the cross-bar and to pass under a pin, W, and the bell-crank is arranged to work in an inclined plane, so that the rod has a slight rising-and-falling motion, whereby it lifts the shoe when coming up against the pin. The straps X, by which the shoe is suspended, are capable of springing readily to allow of the lifting of the shoe in this way.

Having thus described our invention, we claim as new and desire to secure by Letters Patent—

1. The shoe A, provided with the perforated sides E E and end piece F, substantially as described.

2. The shoe A, constructed as described, and arranged with spouts H I and revolving screen K, substantially as herein shown.

3. The arrangement of the bell-crank R, rod S, bar Q, and the pin W, to impart vertical as well as horizontal motion to the shoe, substantially as specified.

JAMES M. KENDALL.
JAMES PEEL.
